(57) **CLAIM**

The ornamental design for a squeeze bottle, as shown and described.

DESCRIPTION

FIG. 1 is a top, front, and left side perspective view of the squeeze bottle.

FIG. 2 is a left side elevational view thereof.

FIG. 3 is a right side elevational view thereof.

FIG. 4 is a rear elevational view.

FIG. 5 is a top plan view thereof; and,

FIG. 6 is a bottom plan view thereof.

The broken lines shown in FIG. 6 are for illustrative purposes only and form no part of the claimed design.
